Q. S. BACKUS.

FIRE PLACE BACK.

No. 16,489.

Patented Jan. 26, 1886.

UNITED STATES PATENT OFFICE.

QUIMBY S. BACKUS, OF WINCHESTER, MASSACHUSETTS.

DESIGN FOR A FIRE-PLACE BACK.

SPECIFICATION forming part of Design No. 16,489, dated January 26, 1886.

Application filed November 21, 1885. Serial No. 183,561. Term of patent 14 years.

To all whom it may concern:

Be it known that I, QUIMBY S. BACKUS, a citizen of the United States, residing at Winchester, in the county of Worcester and State 5 of Massachusetts, have invented and produced a certain new and original Design for an Open-Fire Place Back; and I do declare the following to be a full, clear, and exact description of the invention, such as will enable others skilled in the art to which it appertains to make and use 10 the same, reference being had to the accompanying drawing, and to the letters and figures of reference marked thereon, which form a part of this specification.

- 15 The leading features of my design consist in a rectangular fire-place frame surrounding a vertically-curved fire-back, and provided with ornamental open-work plates in front, as shown in the accompanying drawing.
- 20 A represents a rectangular frame of a fire-place, whose vertical uprights and upper cross-piece are provided with rods *a*, having knobs at their ends and junctures for embellishing the appearance of the same. Within the frame 25 A is a curved fire-back, B. Across the front of the design, between the vertical uprights of the frame, is a plate, C, in the form of diamond cross-work or its equivalent; and above this plate is another similarly-situated plate, 30 D, having a fence-like form, and consisting of a series of parallel palings connected by cross-

35 rods, which plate is inclined inwardly toward the curved fire-back. In front of the fire-place is another rectangular frame, E, extending between the bottom ends of the vertical uprights, and located at right angles to said uprights. This frame contains a transversely-slotted panel or plate, G, and is also provided with an ornamental guard, *b*, similar in appearance to that which has been described as 40 serving to embellish the front of the frame A.

I claim--

- 45 1. The design for a fire-place back, which consists of a rectangular frame surrounding a vertically-curved fire-back which extends inward and downward from the top rail of the frame to the bottom, substantially as shown and described.
2. The design for a fire-place back, which consists of a rectangular frame surrounding a 50 vertically-curved fire-back, whose front is embellished by an ornamental open-work plate, and a second open-work plate inclined rearwardly from the upper front edge thereof, substantially as shown and described.

55 In testimony whereof I affix my signature in presence of two witnesses.

QUIMBY S. BACKUS.

Witnesses:

PHILIP MAURO,
FRED E. TASKER.
